Webpage, "Battery," http://www.kohls.com/upgrade/webstore/zoom_popup.jsp?productId=845524892463327 (cited in Office Action mailed by Japan Patent Office ("JPO") assigned as JPO Design Division Prior Art Document No. HJ20072657 received by the JPO on Mar. 23, 2009) (Mar. 2009).

Primary Examiner — Rosemary K Tarcza*(74) Attorney, Agent, or Firm* — Rader, Fishman & Grauer PLLC**CLAIM**

The ornamental design for a battery, as shown and described.

DESCRIPTION

FIG. 1 is a rear, top, right perspective view of a battery showing my new design;

FIG. 2 is a rear elevational view thereof;

FIG. 3 is a right side elevational view thereof;

FIG. 4 is a top plan view thereof; and,

FIG. 5 is a bottom plan view thereof.

Portions in broken lines are for illustrative purpose only and form no part of the claimed design.
